UNITED STATES PATENT OFFICE.

THOMAS W. THORPE AND GEORGE E. THORPE, OF DES MOINES, IOWA.

METHOD FOR PRODUCING WELLS AND STRAINER SHOE FOR THE SAME.

Application filed January 20, 1926. Serial No. 82,446.

The object of our invention is to provide a method for producing wells wherein an outer casing may be inserted in the ground a proper depth and thereafter a strainer 5 may be placed below the lower end of the outer casing so that the strainer serves as a continuation of the outer casing and when the strainer is inserted in the water bearing formation, practically no resistance is had 10 to the lowering or inserting of the strainer within such formation.

It may be here mentioned that strainers for wells are ordinarily inserted in the well by first driving the outer casing or well casing down through the water bearing formation and thereafter lowering the strainer into the casing and then raising or withdrawing the outer casing leaving the strainer exposed within the water bearing formation and this practice finds many difficulties, one of which is the almost impossibility of 20 withdrawing the outer casing through cement, gravel and sand formations which are ordinarily found just above the water bearing formation.

In driving an outer casing through so called glacial drifts we find that the outer casing may be driven downwardly and yet when it is necessary to elevate the casing so 30 that the strainer is exposed, we find that the glacial drifts which is a clay or sand substance, binds against the outer casing so that the outer casing can not be raised and in many cases the casing becomes broken by 35 the upward pull and in such a case the work already done is practically worthless.

It is our object to overcome the difficulties and disadvantages of having to remove part 40 of the outer casing or raise it in order to expose the strainer. In order to overcome these difficulties we employ a shoe which carries a strainer and the shoe and strainer are inserted within the casing and permitted to go to the lower end thereof, at which time 45 the gravel of the water bearing formation is removed and the weight of the strainer and the shoe will tend to work themselves downwardly through the water bearing formation and thus the strainer is exposed below the 50 lower end of the outer casing and forms practically a continuation thereof.

Still a further object is to produce a well which comprises the inserting in the ground

of an outer casing until it reaches the desired depth which is ordinarily when its 55 lower end rests upon the upper surface of the water bearing formation and thereafter inserting a second casing within the outer casing having a shoe on its lower end and driving the second casing and shoe through 60 the water bearing formation, the shoe being of a greater diameter than the second or inner casing and of less diameter than the outer casing, wherein a strainer may be carried 65 by the shoe and inserted between the outer casing and inner casing during the time it is lowered.

The strainer is of no greater diameter than the shoe itself and will follow the shoe 70 downwardly below the lower end of the outer casing wherein the strainer practically forms a continuation of the casing itself and upon removal of the inner casing, water may be drawn through the strainer and into 75 the outer casing.

Still a further object is to provide a shoe 80 for carrying a strainer through water bearing formations which shoe consists of an open ended tubular member having its lower end sharpened so as to easily pass through the water bearing formation and having a shoulder formed above its lower end upon which rests the strainer. The outer diameter of the shoe and strainer being substantially uniform so that the strainer will follow 85 the path formed by the shoe through the water bearing formation, with practically no resistance or pressure against the strainer itself.

Still a further object is to provide the 90 shoe with a shoulder on its inner surface against which an inner casing may rest where the shoe may be forced down through the water bearing formation and the gravel 95 of the water bearing formation withdrawn through the shoe and through the casing in communication with the shoe.

With these and other objects in view, our invention consists in the construction, arrangement and combination of the various 100 parts of our invention, whereby the objects contemplated are attained, as hereinafter more fully set forth, pointed out in my claims, and illustrated in the accompanying drawings, in which:

Figure 1, is a perspective view of our im-

proved shoe, parts being shown in section to better illustrate the construction thereof.

Figure 2, is a sectional view showing the lower end of an outer well casing and the water bearing formation below the lower end of the casing and the strainer about to be inserted in position.

Figure 3, is a similar sectional view showing the strainer in installed position within the water bearing formation and the lower end thereof sealed and

Figure 4, is a sectional view through the strainer shoe with a concrete strainer resting thereon.

15 In the accompanying drawings we have used the reference character A to indicate generally a metal shoe which is tubular throughout its length and has both of its ends open.

20 The lower end of the shoe A is pointed or sharpened as at 10 so as to easily pass through water bearing formation which we will hereinafter more fully explain.

25 The shoe A includes a shoulder 11 upon which may rest a strainer 12. The strainer 12 rests upon the shoulder 11 and is supported by a portion of the shoe itself which extends up into the strainer 12.

30 The strainer may be secured to the shoe A in any suitable manner. It will be noted that the diameter of the strainer 12 is practically the same as the overall or greatest diameter of the shoe A and this is of importance when lowering the strainer and shoe in through the water bearing formation.

35 The shoe A is formed on its inner surface with a shoulder 13 against which may be fixed a casing 14 which will be hereinafter called the inner casing.

40 The lower end of the inner casing 14 connects with the shoe A and rests upon the shoulder 13 as clearly illustrated in Figures 2, 3 and 4 of the drawings.

45 The inner casing 14 may be fastened to the shoe A in any suitable manner or may simply rest thereon.

50 In connection with the forming or drilling of wells, it is usually necessary to drill or sink an outer casing 15 through the ordinary surface clays 16 and then through the cement, sand and gravel formations 17 which are usually found just above the water bearing formations 18.

55 The outer casing 15 is driven through the surface clays 16 and through the cement, sand and gravel formations 17 until it rests upon the upper surfaces of the water bearing formations 18.

60 The cement, sand and gravel formations are of such a nature that the outer casing 15 may be driven through but cannot be easily withdrawn because the formations 17 and 18 frictionally bind the casing 15 and prevent its withdrawal.

With our method of producing a well the casing 15 simply stops at the lower end of the formation 17 and just above the water bearing formation 18 and it is not necessary to withdraw the outer casing 15.

70 The strainer 12 is inserted in the water bearing formation 18 below the lower end of the casing 15 in the manner we will now describe in detail. The strainer 12 is mounted upon the shoe A in any suitable manner and inserted within the casing 15 and lowered until it rests upon the water bearing formation 18.

75 The strainer 12 and shoe A are open ended so that the gravel in and around the lower end of the shoe A may be withdrawn, washed or bailed out through the strainer and shoe, and as the water bearing formation 18 is withdrawn, the shoe and strainer will be lowered through the water bearing formation until the lower end of the shoe passes clear through the water bearing formation 18 and rests upon the rock or shale 19, at which time the strainer will be completely exposed below the lower end of the casing 15. 80

85 The inner casing 14 may be used for lowering the shoe and strainer and permits any well-drilling tools to be inserted therethrough for bailing out the water bearing formation in and around the lower end of the shoe A or washed by hydraulic process or compressed air used to lift same.

90 The water bearing formation is usually quite loose and by suction, pumping or bailing out the material in and around the lower end of the shoe A, it is permitted to move downwardly due to the weight of the casing 14, until it reaches the desired depth at which time the strainer 12 is exposed the required amount. The casing 14 may then be 95 cut off so that only a portion thereof is left within the shoe, as shown in Figure 3 of the drawings or in case the casing has not been fastened to the shoe A, then it can be removed by simply lifting it out of the shoe. 100

105 It may be here mentioned that the connection between the casing 14 and the shoe A may be screw threaded with threads of a pitch opposite to the pitch of the threads of the above line of tubular sections forming the casing 14 so that by simply rotating the casing 14, it will be unscrewed from the shoe A.

110 This screw threaded connection we have not shown in the drawings and of course, it 115 is only an obvious way of accomplishing the result of disconnecting the inner casing from the shoe A.

115 After the strainer has been inserted within the water bearing formation 18, as shown in Figure 3 of the drawings, then some quick setting cement or lead wool 20 may be dropped into the casing 15 and within the lower end of the shoe A for forming a seal at the lower end of the strainer and shoe so 120

that all water passing therein will have to travel through the strainer 12.

In Figure 4 of the drawings, I have shown a concrete strainer 21 resting in a V shaped notch 22 formed in the shoe A. This simply illustrates a slight variation in the shape of the shoe to accommodate the concrete strainer.

It will be noted that the outer wall of the strainer is substantially flush with the outer wall of the shoe A.

Our method of lowering a strainer in place below the lower end of a casing may be equally as well used in connection with old wells where it is necessary to remove the old strainer and insert a new one and in such a case the shoe A and strainer, may be used with an inner casing 14 without in any way tampering with the outer casing.

It may be here mentioned that in many cases it would be impossible to drive the outer casing a short distance and then withdraw it after the strainer is in place because the outer casing will become weakened by age. It may be said that with our method of inserting the strainer you could actually put a new strainer in position which was greater in length than the old strainer because you can go down and withdraw the water bearing formation below the lower end of the outer casing.

Some changes may be made in the method of producing wells and it is our intention to cover by our claims any method of producing a well, wherein it is not necessary to withdraw the outer casing and where the strainer may be inserted through the outer casing and lowered below the lower end of the outer casing.

We claim as our invention:

1. The method of producing a well comprising the inserting in the ground of an outer casing until it reaches the desired depth, the inserting of an inner casing within the outer casing, the inner casing having a shoe at its lower end, the bottom of which is open, a strainer carried by the shoe, the forcing of the inner casing below the lower end of the outer casing until the strainer is exposed below the lower end of the outer casing the withdrawal of a water bearing formation through said shoe and then removing the inner casing leaving the shoe and strainer for forming a continuation of the outer casing whereby water withdrawn through said outer casing will pass through said strainer.

2. The method of producing a well comprising the inserting in the ground of an outer casing until it reaches a water bearing formation, the inserting of an inner casing within the outer casing, a shoe secured to the lower end of the inner casing, a

strainer on the shoe and on the outside of the inner casing, the forcing of the inner casing below the lower end of the outer casing until the strainer is exposed below the lower end of the outer casing and then removing the inner casing leaving the shoe and strainer and the expanding of the upper end of the strainer to engage the inner surface of the outer casing.

3. The method of producing a well comprising the inserting in the ground of an outer casing until it reaches the desired depth, the inserting in the casing of a shoe having a strainer thereon and driving the shoe below the lower end of the casing until the strainer is exposed and the shoe and strainer form a continuation of the casing and then sealing the lower end of the shoe whereby water entering said casing must pass through said strainer.

4. The method of producing a well comprising the inserting in the ground of an outer casing until it reaches a water bearing formation, the inserting in the casing of an open ended shoe having a strainer thereon and driving the shoe into the water bearing formation below the lower end of the casing until the strainer is exposed, the shoe rests on a shale or rock formation and the shoe and strainer form a continuation of the casing, the withdrawal of the water bearing formation as the shoe constraints are being so driven and the sealing of the open end of the shoe after it rests on said shale or rock formation.

5. A strainer shoe comprising a tubular member having its lower edge sharpened and a shoulder formed above the lower edge of said member for having a strainer rest thereon, a portion of said member extending up into the strainer, and a casing secured to said portion for supporting the shoe and strainer as they are lowered to operative position.

6. The method of producing a well comprising the inserting of a casing in the ground to a depth where its lower end is just above the water bearing formation of the ground, the inserting of a strainer in said casing, an inner casing extending to the bottom of said strainer whereby the strainer is supported and the water bearing formation can be withdrawn through said inner casing but not through the strainer thereby permitting the strainer to pass into the water bearing formation and be exposed below the casing and the expanding of the upper end of the strainer to form a continuation of the outer casing.

Des Moines, Iowa, December 30, 1925.
